UNITED STATES PATENT OFFICE.

HENRY M. SHEER, OF QUINCY, ILLINOIS, ASSIGNOR TO H. M. SHEER COMPANY, OF QUINCY, ILLINOIS, A CORPORATION OF ILLINOIS.

SECTIONAL CANOPY FOR BROODERS.

Application filed November 16, 1923. Serial No. 675,161.

To all whom it may concern:

Be it known that I, HENRY M. SHEER, a citizen of the United States, residing at Quincy, in the county of Adams and State 5 of Illinois, have invented certain new and useful Improvements in Sectional Canopies for Brooders, of which the following is a specification.

My invention relates to an improvement 10 in sectional canopies for brooders, and the object is to provide a simple and comparatively light and inexpensive canopy which may be knocked down and packed and shipped in small compass.

15 This invention consists in an hexagonal canopy preferably of sections of sheet metal detachably connected together at their edges and to a top of any suitable size, with braces and legs for its support and a 20 damper at the top for ventilating purposes.

In the accompanying drawings:

Fig. 1 is a view in perspective;

Fig. 2 is a bottom plan view;

Fig. 3 is a diagram;

25 Figs. 4 and 5 are diagrammatic sectional views, the former of a flat top canopy and the latter of a cone top canopy; and

Fig. 6 is a detail.

The numeral 1 represents the top or center which may be relatively large as shown 30 in Figure 4, or relatively small as shown in Figure 5. This top has a form that the canopy is to take, for example, in the drawings illustrated it is hexagonal, although it 35 might of course be of any angular form.

It preferably has several holes 2 therein, and a damper 3 is pivoted at the center 4 and has a handle 5. This damper has holes 6 corresponding and capable of registering 40 with, holes 2, so that by turning the damper the size of the holes is regulated and the ventilation perfectly controlled.

The sides of the canopy are made up of 45 a plurality of flat sections 7 of sheet metal of which of course there are as many as there are sides to the top, and these are detachably fastened to the top by screws or bolts 8 extending through the flanges 9 of the top and the side edges overlap and are held 50 together by the screws or bolt 10.

To give strength, the lower edges are bound by bars 11 held in place by screws or bolts 12.

Braces 13 are bolted across from side to side, as shown in Fig. 2, diagonally across corners and the legs 14 are preferably made 55 of strips of metal bent into V-shape with the outer ends fastened at the corners of the canopy by screws or bolts 15, and the inner ends to the centers of the braces 13 by means of bolts or screws 16.

In this way, the canopy is made thoroughly rigid when set up as it is braced across each corner and it rests upon legs 60 preferably located at the corners where the overlapping edges of the sections reinforce 65 and constitute strengthening radial ribs for the canopy.

In Figs. 4 and 5, the canopy is illustrated in two different forms, namely, a flat 70 top and a cone-shaped form. It is of course understood that the canopy might be in still other forms.

I claim:

1. A canopy having transverse braces each attached by the ends thereof to two 75 points at the outer rim of said canopy, and having legs secured to and extending downward from said braces and points on said rim of canopy most proximate to junctures of legs with braces.

2. A canopy having transverse braces secured at their ends to adjacent sides thereof, and substantially U-shaped legs, said legs having the outer ends thereof secured 85 to the corners of the canopy, and having the inner ends secured to the transverse braces.

3. A canopy having the sides thereof formed of sections secured together at adjacent edges, braces extending across the 90 said edges between the adjacent sections, and legs secured to and extending downward from the body of the canopy and the braces.

4. A canopy having the sides thereof 95 formed of sections secured together at adjacent edges, braces extending transversely across the said edges between the adjacent sections, and substantially U-shaped legs having the ends thereof secured to and ex- 100
